SEAT SUPPORT

Walter J. Kiefer, Belvidere, Ill.

Application February 10, 1944, Serial No. 521,775

11 Claims. (Cl. 155—95)

This invention relates to mechanisms to be applied to lunch counter stools for automatically returning such stools to a predetermined position when unoccupied.

It is generally considered desirable from the standpoint of neatness of arrangement, as well as for other reasons, to have lunch counter stools, if equipped with backs, all facing in the same direction relatively to the counter when unoccupied, usually facing the counter. It is desirable that such a mechanism be quiet or noiseless in operation and foolproof so that it may not be damaged by careless or mischievous persons. The present invention provides a simplified and inexpensive mechanism for accomplishing that object.

One of the objects of the invention is to provide an automatic self-aligning mechanism on a counter stool so constructed and compactly arranged that it may be positioned inconspicuously under the counter seat.

Another object of the invention is to provide a mechanism of the class described which will be sturdy and simple in design and require no difficult maintenance.

Another object of the invention is to provide a self-aligning mechanism of the class described which will permit the stool to be rotated 180° or more from its normal position and cause it to return to normal position from any displaced position by a rotation of not exceeding 180°.

Another object of the invention is to provide a mechanism for accomplishing the foregoing objects and which will be noiseless in operation and capable of rotation in either direction and of continuous rotation in either direction for more than 360°.

Other objects and advantages of the invention will become apparent from a perusal of this specification.

Referring now to the drawing,

Figure 1 represents a somewhat diagrammatic view on a reduced scale of the relative positions of a lunch counter and stool.

Fig. 2 is a plan view on a reduced scale of a portion of a lunch counter with a pair of stools beside it.

Fig. 3 is a bottom plan view of a lunch counter seat showing one form of the invention applied thereto.

Fig. 4 is a partial sectional view on the broken line 4—4 of Fig. 3.

Fig. 5 is a sectional view of the line 5—5 of Fig. 3.

Fig. 6 is a bottom plan view of the self-

aligning mechanism alone showing it as rotated in a counterclockwise direction about 150° from the position shown in Fig. 3.

Fig. 7 is a bottom plan view of a modified form of the invention.

Referring further to the drawing, the details of construction of the chair itself do not form a part of the invention. For the purpose of explaining the invention it will suffice to consider 10 that the seat 1 is mounted upon a pedestal 2 and is provided with the usual back 3. The upper end of the pedestal is hollow and carries a bushing 4 in which is seated the ball bearings 5 and 6 which furnish a suitable rotative support 15 for the post 7. An enlarged shoulder 8 on the post rests on the top of the upper ball bearing and is preferably integral with a spider consisting of the legs 9, 11, and 12. The outer extremities of the legs of the spider are anchored to the 20 underside of the seat in any suitable fashion as by means of screws 13 extending through spacing members 14.

The bushing 4 carries on its upper end either integral therewith or secured thereto a stationary ring gear 15.

In the form of the invention shown in Figs. 3, 4, and 6 two of the legs of the spider carry rotatable spur gears 16 and 17, these gears being rotatably positioned upon the spider legs 30 in any suitable manner, for example, by means of the screws 18 and bearings 19, being slightly spaced apart from the spider legs by spacing washers 21 as shown.

Each of the gears 16 and 17 is provided with 35 a spring pilot post such as 22 shown in Fig. 5 having a spacing shoulder as shown, permitting rotation of a sleeve 23 about which is wrapped the end of one of the restoring springs 24. The opposite ends of these springs are anchored on 40 the bracket 25 secured to the leg 9 of the spider.

The screw 18, bearing 19 and spacing washer 21 are designed to hold each of the gears free to rotate and in a position slightly spaced below the spider legs.

45 The modified form shown in Fig. 7 differs from that shown in Fig. 3 only in that it employs a single restoring spring 26, a single spur gear 27 mounted on one of the spider legs 28 in mesh with the stationary gear 29. The 50 bracket 31 retains the other end of the restoring spring 26.

Referring now to the form of the invention shown in Figs. 3, 4, and 6, assuming that the seat is arranged normally to face the counter, when 55 a patron is leaving the stool and rotates the stool

from its normal position, as the seat rotates upon the pedestal the gears 16 and 17 will be rotated to an extent determined by the degree of rotation of the chair seat. However much this rotation is, each of the restoring springs will be extended beyond its "at rest" length and if the chair is released while the mechanism is in the position shown, for example, in Fig. 6, the restoring springs acting on the posts 22 will cause the gears 16 and 17 to be rotated back toward their normal position in mesh with the stationary gear and thus restore the seat to normal. If the seat has been rotated from normal less than 180° it will return to normal by reversing the rotation through which it has just moved, but if it has been rotated more than 180° from normal the position of the posts 22 relatively to the restoring springs will cause the chair to continue its rotation in the same direction until restored to normal. This will be clear from examining Fig. 6 and assuming a rotation of more than 180°.

It will now be clear in view of this construction that the chair seat rotated from normal and then released will always return to normal position by the shortest route, but will never require more than 180° of rotation after release. Also, no harm will be done to the mechanism if anyone in a playful mood should rotate the chair continuously in either direction an unlimited number of times.

In view of the simple gear construction employed it may be expected that the mechanism will give no maintenance trouble and will require lubrication only at long intervals, sufficient to assure noiseless operation and freedom from wear.

Another advantage residing in this construction will be observed in the fact that the tension of the springs cannot be increased accidentally or mischievously beyond the tension which they attain at 180° rotation from the normal position of the chair.

The modification shown in Fig. 7 operates in the same manner as does the other embodiment of the invention, differing only in the use of one planetary gear 21 and one restoring spring pivotally connected thereto. Whether a pair of planetary gears and springs or just one set is employed is a matter of choice. The tension of the springs used may be varied, of course.

The normal "at rest" position for the mechanism will be attained, as illustrated in Figs. 3 and 7, when the pivotal connection of the restoring spring with the planetary gear lies on a straight line between the opposite end of the spring and the axis of the planetary gear to which that spring is attached. While a dead center position could also be reached when the planetary gear has been rotated 180° from normal that position would not normally be attained or maintained unless the chair were accurately positioned at that angular position intentionally. In actual practice this latter condition would seldom occur, and would be harmless if it did.

While it is stated above that the preferred normal position of the chair may be to have it facing the counter, it is obvious that the normal position may be at any other angular position relatively to the counter edge, dependent upon the preference of the owner of the equipment. This is easily arranged by lifting the chair seat and hence the post 7 high enough to disengage the planetary gears from the stationary gear, and when the springs have pulled the two planetary gears into the relative positions shown in Fig. 3 the seat may be rotated, with the gears

out of mesh until the desired normal angular position is reached, after which the seat may be lowered until the gears are again in mesh. This position will then establish the normal position for that particular stool. It should be noted that all the gears are equal in size.

One advantage possessed by this mechanism and not found in some other devices of this character resides in the fact that the chair occupant may rotate the chair from normal with scarcely noticeable effort. It should be understood that these specifications and the drawing disclose the invention in only two of the forms in which it may be embodied, but that the details of construction of these forms or other forms may be varied without departing from the spirit of the invention as claimed.

Having shown and described my invention, I claim:

20 1. A self-aligning counter stool comprising a pedestal, a stationary spur gear mounted on said pedestal extending in a plane perpendicular to the pedestal axis, a chair seat pivotally supported on the pedestal, a planetary gear pivotally supported on said seat in mesh with said stationary gear, a coil spring operatively connected with the said planetary gear eccentrically to its axis, and means for anchoring the opposite end of said spring on said chair seat, said spring being arranged to rotate said planetary gear and the seat with it back to a normal position affording minimum distension of the spring whenever the seat has been displaced from normal and is free for such restoring rotation.

35 2. A self-aligning counter stool comprising a chair seat, a pedestal pivotally supporting the seat, a stationary gear mounted near the upper end of said pedestal perpendicular thereto, a planetary gear pivotally carried by the chair seat on its underside in mesh with said stationary gear, and a coil spring having one end anchored in a fixed position relatively to the chair seat and its other end pivotally connected with said planetary gear eccentrically of the axis thereof whereby the tendency of the spring to return to normal distension may rotate the planetary gear to restore the seat to a predetermined normal angular position relatively to the pedestal.

3. A self-aligning counter stool comprising a pedestal, a chair seat pivotally supported on the top of said pedestal, a stationary ring gear mounted on the upper end of said pedestal, a planetary spur gear in mesh with said stationary gear pivotally supported on the seat eccentrically of the axis of the seat, a coil spring, means for anchoring one end of said spring in a fixed position on said seat, and means pivotally connecting the other end of said spring with said planetary gear eccentrically of its axis, said spring being arranged when distended from its normal minimum length to rotate the planetary gear about the stationary gear and acting through the axis of the planetary gear to restore the seat to a position to re-establish the minimum distension of said spring.

4. A self-aligning counter stool comprising a pedestal, a seat pivotally mounted on said pedestal, a stationary gear mounted concentrically with the axis of the seat, a planetary gear in mesh with the stationary gear pivotally supported on said seat eccentrically of the axis of the seat, a coil spring having one end supported at a fixed point upon said seat and having its other end pivotally connected with said gear eccentrically to the axis thereof, said spring tending to main-

tain the planetary gear in a normal position with said pivotal connection of the spring lying between the axis of the planetary gear and the opposite end of the spring.

5. A self-aligning counter stool comprising a pedestal, a seat pivotally mounted on said pedestal, a stationary ring gear positioned on said pedestal in a plane perpendicular thereto, a planetary gear meshed with said stationary gear pivotally supported on said seat eccentrically of the seat axis, a coil spring, means for retaining one end of said spring at a fixed point relatively to said seat, and means operatively connecting the other end of said spring to the planetary gear eccentrically of its axis, said spring being arranged to act through said gears to maintain the chair seat normally in a predetermined angular position relatively to the pedestal while permitting against the tension of the spring rotation of the seat carrying the planetary gear about the seat axis.

6. A self-aligning counter stool comprising a pedestal, a seat pivotally mounted on said pedestal, a stationary ring gear positioned on said pedestal in a plane perpendicular thereto, a planetary gear meshed with said stationary gear pivotally supported on said seat eccentrically of the seat axis, a coil spring, means for retaining one end of said spring at a fixed point relatively to said seat, and means operatively connecting the other end of said spring to the planetary gear eccentrically of its axis, said spring being arranged to act through said gears to maintain the chair seat normally in a predetermined angular position relatively to the pedestal while permitting against the tension of the spring rotation of the seat carrying the planetary gear 360° about the seat axis.

7. A self-aligning counter stool comprising a pedestal, a seat pivotally mounted on said pedestal, a stationary gear mounted on the pedestal perpendicularly thereto, a planetary gear in mesh with the stationary gear pivotally supported on the seat eccentrically of the axis of the seat, a coil spring, means for retaining one end of the spring at a fixed point on the seat eccentrically of its axis, and means operatively connected with the planetary gear eccentrically of its axis for retaining the other end of the spring, the whole

being arranged whereby the seat is free for rotation in either direction and more than 360° with the spring acting through the planetary gear tending to retain the seat in a predetermined angular position relatively to the pedestal.

8. A self-aligning counter stool comprising a pedestal, a seat pivotally supported on said pedestal, a stationary gear on the pedestal, a rotatable planetary gear carried by the seat in mesh with said stationary gear, and a coil spring anchored on the seat and operatively connected eccentrically to the planetary gear arranged for rotating the seat about its axis and for resiliently retaining the seat at a predetermined normal position.

9. In a self-aligning counter stool, a pedestal, a stationary gear on the pedestal, a frame for attachment to the under side of a chair seat pivotally supported on the pedestal, a planetary gear in mesh with the stationary gear and rotatably carried by said frame, and a coil spring having one end anchored to said frame and its other end operatively connected eccentrically to the planetary gear arranged for rotating the frame about its axis and for resiliently retaining it at a predetermined normal position.

10. A self-aligning counter stool comprising a pedestal, a stationary spur gear mounted concentrically on the pedestal, a seat pivotally supported on said pedestal, a toothed member pivotally mounted for rotative movement on the seat in mesh with said gear, and spring means anchored on the said seat operatively connected to said toothed member eccentrically of its pivot arranged for rotating the seat about the pedestal and resiliently retaining the seat at a predetermined normal position.

11. In a self-aligning counter stool, a pedestal, a stationary gear on the pedestal, a frame for attachment to the under side of a chair seat pivotally supported on the pedestal, a toothed member pivotally mounted on said frame for rotative movement in mesh with said gear, and spring means anchored on said frame and operatively connected with said member eccentrically of its pivot arranged for rotating the frame about the pedestal and for resiliently retaining the frame at a predetermined normal position.

WALTER J. KIEFER.
